UNITED STATES PATENT OFFICE

PATRICK FLAHERTY, OF LOS ANGELES, CALIFORNIA

DESIGN FOR A GAME WHEEL

Application filed January 2, 1931. Serial No. 38,176. Term of patent 14 years.

To all whom it may concern:

Be it known that I, PATRICK FLAHERTY, a citizen of the United States, residing at Los Angeles, in the county of Los Angeles and State of California, have invented a new, original, and ornamental Design for a Game Wheel, of which the following is a specification, reference being had to the accompanying drawing, forming part thereof.

Fig. 1 is a plan view, and Fig. 2 is a diametrical cross sectional view of a game wheel embodying my new design.

I claim:

The ornamental design for a game wheel, as shown.

PATRICK FLAHERTY.
